CEILING VENT

Filed April 13, 1927

FIG. 1.

FIG. 2.

FIG. 3.

INVENTOR:

JAMES JENNER,

By: Otto de Ringer,
his Atty.

UNITED STATES PATENT OFFICE

JAMES JENNER, OF LOS ANGELES, CALIFORNIA, ASSIGNOR OF ONE-HALF TO KARL SCHUMACHER, OF LOS ANGELES, CALIFORNIA

CEILING VENT

Application filed April 13, 1927. Serial No. 183,568.

This invention relates to devices used in ceilings and walls for controlling the air circulation in a room.

One of the objects of this invention is to provide a vent that may be imbedded in the structure of a building, as in the plaster of walls and ceilings, operative by a mere pulling of a member protruding from the vent.

Another object is to facilitate an operation of the vent, as the closing or opening movements, by one action.

Another object is to provide a vent that may be closed or opened by a chain, or other similar suitable flexible or for that matter any other protruding member from the vent.

Other objects will appear from the following description and appended claims as well as from the accompanying drawing, in which—

Fig. 1 is a top plan view of a vent with a disc rotatably mounted on the vent and with a ratchet mechanism by which the disc can be moved to close or open passages through the vent by a rotation of the disc in the same direction, arranged according to this invention.

Fig. 2 is a section on line 2—2 of Fig. 1 with the vent plate imbedded below the plaster of a building structure.

Fig. 3 is a similar section with the vent plate disposed on the surface of the plaster of a building.

As illustrated in the drawing, the vent plate 4 is provided with passages or apertures 5. A disc 6 is turnably mounted to rotate around a central pin 7 on the vent plate 4. The disc is provided with openings or apertures 8 to correspond with the openings in the vent plate. A ratchet ring 9 is provided with notches 10 of double the number of the groups of apertures in the disc and vent plate. An operating bar 11 is shiftably mounted in the blocks 12 and 13, operative by a chain 14, the chain extending through the opening 15 in the vent plate out of the front side of the vent plate. A ratchet pawl 16 is pivotally mounted on the operating bar at 17, controlled by the spring 18 disposed between the ratchet pawl and the operating bar to force the pawl into the notches 10. A

spring 19 serves to retain the disc in certain positions to which the disc has been advanced by the movements of the ratchet pawl 16 and operating bar 11. The ratchet pawl 16 and operating bar 11 are returned to inoperative position by the spring 20.

This whole structure may be imbedded in a wall or a ceiling below the plaster so that the vent plate 4 becomes recessed or set back in relation to the plaster 21 as illustrated in Fig. 2.

On the other hand, the vent plate 4 may be made of ornamental design and then placed over the surface of the plaster in a position shown in Fig. 3, so that the vent plate is over the surface of a building structure.

When a vent of this type is disposed in a ceiling, the chain 14 may be pulled to close or open the vent.

Pulling the chain and thereby the operating bar 11 with the pawl 16 brings the pawl into engagement with one of the notches 10 of the ring 9 on the disc 6. By a further pulling the disc is rotated around the central pin 7 on the vent plate 4. Since a double number of the notches 10 are provided corresponding to the groups of apertures in the disc 6 and vent plate 4, the disc is only rotated in one operation half the distance between the groups of openings, which means that the disc is moved or turned in one operation to bring the openings 8 of the disc over the closed space between the openings 5 in the vent, that is over the solid material of the vent plate, so as to shut-off the passages through this vent.

By a second operation on pulling the chain 14 again so as to advance the operating bar 11 with the pawl 16 to come into engagement with another of the notches 10, the disc is again rotated around the pin 7 and again moved half the distance between the groups of openings, so that the openings 8 in the disc come this time again to a position over the openings 5 of the vent plate.

The groups of openings in the disc 6 and in the vent plate 4 are therefore preferably larger near the periphery and smaller towards the center as illustrated in Fig. 1.

Having thus described my invention, I claim:

- 5 1. A vent of the class described comprising a vent plate, a disc turnably mounted on the vent plate, a ratchet mechanism for rotating the disc in relation to the vent plate, and a chain extending from the ratchet mechanism through the vent plate to protrude from the surface of the vent plate.
- 10 2. In a vent of the class described, an apertured vent plate, a disc turnably mounted on the vent plate with apertures to correspond with the apertures in the vent plate, operating means for rotating the disc, means for retaining the disc in advanced positions, and means for returning the operating means to inoperative position while the disc remains so retained.
- 15

In testimony that I claim the foregoing as
20 my invention I have signed my name.

JAMES JENNER.
